Primary Examiner — Elizabeth A. Albert

(74) *Attorney, Agent, or Firm* — Smiths IP; Lawrence Chan

(57) **CLAIM**

The ornamental design for a planter, as shown and described.

DESCRIPTION

Fig. 1 is a top perspective view thereof;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and;

FIG. 9 is a top perspective view thereof, shown in an environment of use.

The features shown in broken line in FIG. 9 depict environmental subject matter only and form no part of the claimed design.

1 Claim, 9 Drawing Sheets
